UNITED STATES PATENT OFFICE.

CARL ARTHUR ANDERSON, OF CHICAGO, ILLINOIS.

SPEED INDICATOR AND RECORDER.

1,167,671.

Specification of Letters Patent. Patented Jan. 11, 1916.

Application filed December 11, 1913. Serial No. 806,027.

To all whom it may concern:

Be it known that I, CARL ARTHUR ANDERSON, a citizen of the United States, residing at Chicago, in the county of Cook and State of Illinois, have invented certain new and useful Improvements in Speed Indicators and Recorders, of which the following is a specification.

My invention relates to improvements in mechanism for indicating and recording the speed of vehicles, per hour, and one of the objects of the invention is to simplify and construct a mechanism of this character in such compact form that it will require as little space as possible.

A further object of the invention is to provide a driving cylinder, over which a marking web or strip is trained, and by means of which it is advanced, from an unwinding to a winding roller, and incorporating in the driving-cylinder certain of the mechanism by means of which the device of my invention is rendered operable.

A further object of the invention is to provide improved means for actuating a marker arm whereby movement thereof will cause a graphic line to appear upon the web or band in such relation with respect to mileage and time indications as to indicate the mileage and the speed attained during travel.

Further objects of the invention will be more fully described in connection with the accompanying drawings and will be more particularly pointed out and ascertained in and by the appended claims.

In the drawings: Figure 1 is a vertical sectional view on line 1—1 of Fig. 3 showing the winding and unwinding rolls in elevation. Fig. 2 is a view similar to Fig. 1 with all of the internal mechanism shown in elevation, but looking at the device in a direction opposite to that in which Fig. 1 is viewed. Fig. 3 is a sectional view on line 3—3 of Fig. 2. Fig. 4 is a fragmentary view in elevation of a band or web on which mileage and time indications, together with a graphic line are shown. Fig. 5 is a view partly in section and partly in elevation of the left hand end of the driving shaft illustrating connections therewith. Fig. 6 is a view in side elevation illustrative of one

form of drive connection with one of the wheels of the vehicle. Fig. 7 is a plan view thereof. Fig. 8 is a detail sectional view 55 through the driving shaft to show the shifting lever mounted thereon.

Like characters of reference designate similar parts throughout the different figures 60 of the drawings.

As illustrated, 1 designates a casing in which the device of my invention is disposed. A driving shaft is indicated at 2, and may be journaled in the side walls of the casing 1 in any suitable manner. A 65 flexible connection 3 leads from the drive shaft 2 to a gear shaft 4 on which a gear 5 is mounted. Gear 5 meshes with a gear 6 which may be on the axle 7 of a vehicle. A frame 8 serves to support the attachment for 70 transmitting drive from the axle to the indicator, as shown more particularly in Figs. 6 and 7.

Rotatable about the drive shaft 2 is a driving cylinder 9 which is hollow in form and 75 which is provided on its periphery with web-advancing studs 10. A gear wheel 11 is loose on shaft 2 and is connected with the driving cylinder 9 to transmit drive thereto by means such as a clock work 12, briefly 80 indicated in Figs. 1 and 3. A wheel 13 meshes with wheel 11 to transmit drive. A web or band 14 is trained over the driving cylinder 9 and is provided with suitable openings 15 for engagement with the studs 85 10, so that when the cylinder 9 is rotated the web or band will be advanced. The indicating web is initially wound upon an unwinding roller 16, which is suitably journaled at 17, in the casing 1, and I provide a winding 90 roller 18, journaled in the casing 1 as at 19, to take up the web unwound from the roller 16. In order to take up slack between the winding roller 18 and the driving cylinder 9 I preferably provide the roller 18 with a 95 pulley 20, over which and a pulley 21, fixed to wheel 11, is trained a spring-transmission element 22.

One end of the shaft 2 is journaled in a bearing 23, secured to the casing 1, and the cylinder 9 is loosely mounted on the drive shaft 2 between gear wheel 11 and a fixed governor hub 24, which may be secured to the shaft 2 by a pin 25. Near the opposite

end of the cylinder 9 on shaft 2 I slidably mount a governor hub 26 and provide the same with a pin 27 which extends through a slotted portion 28 of the shaft 2. The slideable and fixed hubs 24 and 26 are connected by resilient governor spring arms 29, each of which is provided with a centrally disposed weight 30. The ends of the spring arms 29 may be secured to the hubs by clips 31 which are pivotally mounted to the hub as at 32.

It will be seen that expansion of the weighted central portions of the arms 29 will result from rotation imparted to the governor from drive transmitted to the shaft 2 when the vehicle is in motion. Such distension of the arms will serve to draw the slideable hub 26, inwardly from the left hand end wall of the cylinder 9, in accordance with the expansion of arms 29. I will now describe the marker arm operating mechanism which is controlled by this sliding movement of the hub 26, under the action of the governor.

A shifting rod 33 is movable longitudinally and axially in a bore 34 of the shaft 2, and is actuated by the hub 26 through the medium of the pin 27 which is passed through the shifting rod 33, as will be seen more clearly by reference to Fig. 5. Rod 33 is provided with shoulders 35 which are engaged by a fork 36 in a shifting lever 37. Shifting lever 37 is pivotally hung at 38 to swing from a bracket 39 projecting from the casing 1. The lower end of the lever 37 is pivotally connected at 40 with a link rod 41, the opposite end of the latter being connected at 42 with a marker operating arm 43. The marker operating arm 43 is pivotally mounted at 44 upon an arm 45 which extends inwardly from, and is mounted upon the casing 1.

I have shown operating arm 43 provided with a branch 46 connected by a spring 47 with an arm structure 48, mounted on casing 1, for adjustment and calibrating purposes, primarily.

A marker arm is indicated at 49 and is pivoted at 50 to a lever 51 which latter is pivoted at 52 to a support 53, mounted on the casing 1. The free end of the marker arm 49 is provided with any suitable form of a marking device 54 which will serve to form a graphic line 55 across the face of the indicating web 14.

Time or speed indications 56 are disposed longitudinally of the web 14 and mileage indications 57 are disposed transversely of the web 14.

From the foregoing description it will be readily seen that the cylinder 9 is driven constantly from the clockwork to advance the web 14 and the governor, being driven from shaft 2 of the vehicle, will serve to move the marker arm 49 across the web or band and the pivotal connections of the arm

43, at 58, with the marker arm 49, and the mounting of the marker arm as shown more clearly in Fig. 2, will serve to move the marker 54 in a substantially straight line to and fro across the web 14.

It will be seen that all of the governor mechanism is concealed within the driving cylinder 9 and that transmission is effected to the marker arm shifting mechanism wholly by axial movement of the slideable hub 26 on the driving shaft itself. Thus I do not have to provide a driving shaft in spaced relation with respect to the driving drum or cylinder.

It is believed that the device of my invention will be clearly understood from the foregoing description and while I have herein shown and described one specific form of my invention, I do not wish to be limited thereto except for such limitations as the claims may import.

I claim:

1. In a speed indicator and recorder, an inclosing casing, a driving cylinder, an indicating web trained thereabout, winding and unwinding rollers for the extremities of said web, a governor mounted within said cylinder, an elongated bracket means carried by said casing, a lever and an operating arm pivoted at opposite extremities of said bracket, link means connecting said lever and said arm the latter arching partially about said cylinder, and a marking arm for operation upon said web as controlled by said first arm and oppositely arching about said cylinder.

2. In a speed indicator and recorder, an inclosing casing, a shaft journaled in the ends of said casing, a cylinder loosely mounted upon said shaft, independent driving means for said shaft and said cylinder, a governor mounted upon said shaft and within said cylinder, bracket means extending through said casing, a lever pivoted at one extremity of said bracket for operation by said governor, an operating arm also pivoted to said bracket and arching partially about the upper portion of said cylinder on one side thereof, a web trained over said cylinder for rotation therewith, and a marking arm adapted to operate upon said web under control of said first arm and oppositely arching about the upper portion of said cylinder upon the other side thereof.

3. In a speed indicator and recorder, an inclosing casing, a shaft journaled in the ends of said casing, a driving cylinder loosely mounted upon said shaft, a web trained over said cylinder, winding and unwinding rollers for the extremities of said web, a governor mounted for rotation with said shaft and within said cylinder, means slideable through a partial bore of said shaft for rotation therewith and longitudinally actuated by said governor, bracket means ex-

tending through said casing, a lever pivoted at one extremity of said bracket and loosely embracing said slidable means, an operating arm also pivoted to said bracket, link means 5 maintaining said lever and said arm in substantially parallel relation, said arm arching about one side of the upper portion of said cylinder, means connected to said arm for calibrating purposes, and a marking arm 10 pivoted above said cylinder and pivotally

connected to first said arm to oppositely arch over the other side of said cylinder and to contact with said web under control of said operating arm.

In testimony whereof I affix my signature 15 in presence of two witnesses.

CARL ARTHUR ANDERSON.
